UNITED STATES PATENT OFFICE.

CHARLES C. HEBBARD, OF JOPLIN, MISSOURI.

ORE-CONCENTRATOR.

1,323,470.

Specification of Letters Patent.

Patented Dec. 2, 1919.

Application filed June 28, 1919. Serial No. 307,272.

To all whom it may concern:

Be it known that I, CHARLES C. HEBBARD, a citizen of the United States, residing at Joplin, in the county of Jasper and State 5 of Missouri, have invented certain new and useful Improvements in Ore-Concentrators, of which the following is a specification, reference being had to the accompanying drawings.

- 10 This invention relates to concentrating tables, and particularly to the end motions thereof, that is the means whereby the movement of the discharge end of the table is given a lateral component.
- 15 The general object of this invention is to provide very simple and easily applied mechanism to this end which, upon a jar or reciprocating motion being given to the table at its head end, will cause the discharge end of the table to have a lateral component, and particularly which will cause any point at the discharge end of the table to have a movement in an ellipse, thus giving a "panning" motion to the discharge 25 end of the table, which motion is particularly essential for the proper separation of the concentrates.

A further object is to provide improved means for supporting the deck whereby the 30 deck may have a free movement in all directions to thus enable the deck to move laterally as well as longitudinally.

And still another object is to provide mechanism for giving the lateral component 35 to the table, comprising a crank-like member supported on a shaft, mounted upon the base, the free extremity of the crank-like member being connected to the table, and the crank-like member being so set as to cause 40 a lateral movement of the discharge end of the table when the head end of the table is reciprocated longitudinally.

A further object is to provide a mechanism of this character wherein the amount 45 of movement of the table, and particularly the amount of lateral movement, may be adjusted and controlled.

Another object is to provide very simple means whereby the deck may be laterally 50 tilted and adjusted.

My invention is illustrated in the accompanying drawings, wherein:—

Figure 1 is a top plan view of a concentrating table with the deck removed, showing one form of my device applied thereto;

Fig. 2 is an end elevation of the table;

Fig. 3 is a fragmentary top plan view showing another form of my device showing a portion of the table;

Fig. 4 is an end elevation of the table 60 shown in Fig. 3;

Fig. 5 is a vertical sectional view through the table showing my device in elevation; and

Fig. 6 is a section on the line 6—6 of 65 Fig. 4.

Referring to these drawings, it will be seen that the concentrating table comprises longitudinally extending sills or base beams 10. Disposed above the sills 10 are a plurality of transverse supporting beams 11. The sills 10 have bolted to them a clamp 12, held in place by means of bolts 13 or other suitable means. Disposed in these clamps are a plurality of vertically extending, flexible supports 14, each support, as illustrated in Fig. 6, being composed of a group or bundle of small rods 15, square in cross section, and arranged in abutting relation to form a support 14, which is also 80 square in cross section, these rods being preferably of second growth hickory. These supports may have any desired length and may be square in cross section for their entire length, or may have the middle portion of the composite support turned down or reduced to any desired extent to secure the desired resiliency in the support. The supports are wrapped or banded at intervals, as at 16, so that the individual pieces or 90 rods of the support are held firmly together. These individual rods or pieces may also be glued to each other. Such a support as this will yield equally well in any direction, either longitudinally or laterally of the deck 95 axis or at an angle between these two movements. The upper end of the supports are clamped between metallic plates 17, bolted or otherwise fastened to the beams 11 and projecting out beyond these beams, these 100 clamping plates being in turn clamped upon the supports by bolts 18.

The deck beams 19 are each provided adjacent one end with downwardly extending ears 20 mounted on clamps 21 which embrace the beams 19, these ears 20 extending downward between the clamping plates 17 and being pivoted thereto by a transverse bolt 22, these ears, of course, extending into recesses formed in the upper edge face of the 110 corresponding beam 11. Adjacent the opposite end of each beam 19, there is pro-

vided a clamp 23 carrying a roller 24 disposed in a recess in the beam 19, and between the clamping plates 17 at this end of the beams 11 there is provided a cam-shaped member 25 mounted on a square shaft 26. This shaft extends the full length of the table.

It will be understood that each of the deck supporting beams 19 is provided with a grooved roller 24, and each of the corresponding beams 11 is provided with a cam engaging in the groove of the corresponding roller so that when the shaft 26 is rotated, all the cams 25 will move together and thus the table may be tilted. The tongue and groove engagement between the cam and roller will cause the deck and the beams 11 to move longitudinally together. The shaft 26 is provided at any desired point with a handle whereby it may be oscillated and this handle may engage with an arcuate rack or equivalent device for the purpose of holding the handle in adjusted positions. By this means the deck may be laterally tilted to any desired amount.

In Fig. 1, I show one means for securing a lateral movement at the discharge end of the table. This comprises a transverse shaft 27 mounted in bearings 28 carried by the sills 10, this shaft extending at an angle to the longitudinal axis of the table and having at one end an upwardly extending arm 29 which is fast to the shaft 27, and which is provided at its upper, free end with a laterally projecting stud 30, engaging a socket formed in a socket member 31 carried upon the end beam 11. This stud 30 has a hemispherical extremity and the socket is also hemispherical. Extending from the free end of the arm 29, downward and outward toward the shaft, is an integral rod 32 which, at its lower end, is formed with an eye through which the shaft 27 passes. This end of the shaft is screw-threaded, and a nut 33 is mounted upon this screw-threaded end, bearing against the eye or bearing on the end of the rod 32. This nut 33 is a compensating nut which, when turned up, acts to force the stud 30 into the socket member 31, thus keeping the ball and socket closely engaged and taking up wear.

With this end motion, it will be obvious that upon a longitudinal jar being given to the table, as by any ordinary head motion, as for instance, by the head motion illustrated in my Patent, No. 1,286,617, granted on the 3rd day of December, 1918, the discharge end of the table will move longitudinally, and because of the crank 29, will also be given a lateral movement on the line $a-a$ in Fig. 1. The longitudinal, reciprocating movement given to the deck is commonly from $\frac{3}{4}$ " to $\frac{1}{2}$ " in length, and the crank motion illustrated will produce a lat-

eral movement of from $\frac{3}{8}$ " to $\frac{1}{2}$ ", but this can be varied by changing the angle of the shaft 32. Thus, in Fig. 1 I have illustrated one end of the shaft as being loosely mounted in the pillar block 28 and the opposite end of the shaft 32 as being carried in a pillar block 28 which is slideable upon an arcuate track 28^a, along which the pillar block is adjustable. Thus, the shaft 32 may be shifted from the position shown in full lines to either of the positions shown in dotted lines. The pillar block is held in its adjusted position by means of a set screw 28^b or other suitable means.

In Fig. 3 I show another, and in many respects, a better mechanism for securing lateral motion at the discharge end of the deck and securing the elliptical "panning" movement which is particularly desirable for this purpose. In this case, I mount upon the sills 10, beams 34 forming a platform, and fasten upon this platform a base plate 35 having an upwardly extending, approximately semi-circular socket 36. Disposed in this socket is the cylindrical end of a crank arm 37, whose other end is formed with upwardly projecting lugs 38 which embrace the end beam 11, as illustrated in Fig. 4. The arm or lever 37 is formed with a laterally extending arm 39 and pivoted to this is a link 40 which is screw-threaded at its extremity and extends loosely through a bracket 41 attached to the under side of the end beam 11. Engaging this screw-threaded end of the link 40 is a nut constituted by an interiorly screw-threaded hand wheel 42. The inner faces of the lugs 38, as will be seen in Fig. 3, are convexly rounded and embrace the beam 11 snugly. As illustrated in Fig. 3, the arm 39 is laterally extended and formed with a plurality of perforations 43, and a bolt 44 extends through the end of the link 40 and is engageable in any one of the perforations. With this construction also, when a longitudinal thrust is given to the deck beams 11 at the head end of the table, as by any ordinary head motion, the discharge end of the table will be caused to shift laterally.

It will be noted that in the construction shown in Fig. 1, the socket 31 is not connected to the projecting lug 30, and that in Fig. 3, the lugs 38 have sliding and rocking engagement with the deck beam 11. It is because of the fact that there is not a rigid engagement between the lug 30 and the socket 31, and between the lugs 38 and the deck beam 11, that I secure an elliptical movement or "panning" action of the deck at the discharge end thereof.

If the deck was moved longitudinally and laterally on a solid plane surface and the lug 30 and the socket 31, the upwardly projecting lugs 35, and beam 11, were positively connected together, the discharge end

of the deck would move in a diagonal line and return on the same line, in other words there would be no elliptical or "panning" movement, but inasmuch as the parts mentioned are not fastened together and the deck is supported or suspended on supports, it yields freely in all directions, then when the horizontal impulse occurs, the pressure of the lug 30 in the socket 31 (in the construction shown in Fig. 1) gives the end of the table a lateral thrust and at the same time a momentum, owing to the weight of the table combined with the load of about 400 pounds of pulp on it, and this tends to slightly separate the socket 31 from the lug 30 and the spring brings the table back for the next impulse, thus giving the end of the table a swinging motion on the flexible supports and securing the elliptical movement which is essential. This is plainly shown in tables of this character by mounting a card upon the deck and fixing a pencil in a stationary position above the deck so it will bear upon the card.

The same action is secured in the construction shown in Fig. 3 by the slippage which occurs between the lugs 38 and the deck beam.

In order to secure an adjustment of the degree of lateral movement in the construction illustrated in Fig. 3, the pin or bolt 44 is changed from one hole 43 to another to thereby increase or decrease the length of the crank, and this causes the lever or arm 37 with its projecting lug to give more or less throw to the crank and consequently a more or less lateral movement. The tightening or loosening of the hand wheel 42 does not change this lateral movement and is only for the purpose of bringing a tension between the supports and lugs 38.

It is to be particularly noted that some means must be provided for adjusting the plane of the deck, and that I have provided means which are mounted upon the upper end of the supports 14 for this purpose. In all construction of which I am aware, wherein there is means for adjusting or tilting the deck, the deck has only a horizontal movement and the means for tilting the deck are located in or near the base of the machine and in a fixed position. It would be impossible, however, to use any such means for adjusting the deck with my mechanism because the deck of my concentrator has both a longitudinal movement and a lateral movement. One of the fundamental requirements in order to retain a good recovery in the concentration of ore by a concentrating table is that the deck must be kept nearly as possible at all times and in all positions flat and level. In the practical embodiment of my deck, the deck beams 19 are supported on each side by at least five flexible supports 14, and it is necessary that the

deck must be kept flat and level under all circumstances. If not so held, the ore will not travel freely toward the discharge end of the table. If the deck becomes warped or any part of its surface sags or becomes uneven, or the supports do not hold it perfectly level and flat during its movement, satisfactory results cannot be secured, where the deck is submitted to a longitudinal as well as a lateral thrust. Therefore, in a device of this character it is absolutely necessary that the tilting elements, namely, the cams 25, and the means for adjusting these cams, should follow the deck through both movements, in other words my end motion could not be used with a deck of a concentrating table unless means were provided for laterally adjusting the deck, said means being mounted upon the upper ends of the flexible supports or so mounted as to move with the deck.

One of the particular advantages due to the use of the end motions illustrated is that by the means of this end motion the discharge end of the table will be given a panning movement, that is any point at the discharge end of the table will move in an elliptical orbit, the longer axis of the ellipse being disposed on a line diagonally to the longitudinal axis of the table. This panning movement is very essential to the proper concentration of the ore. In order to secure such an elliptical movement of any point on the discharge end of the table, it is absolutely necessary that the deck shall be supported by means of supports which will yield readily in all directions. It is obvious that supports which will only yield longitudinally would be of no value, and that the use of supports yielding laterally would be equally of no avail. By having the supports constructed as described, however, they will yield equally well in all directions, and thus the deck will be given a free panning movement as previously described.

While I have illustrated two embodiments of my invention which I have found to be thoroughly effective in actual practice, yet I do not wish to be limited thereto, as it is obvious that many changes might be made in the details of construction and arrangement of parts without departing from the spirit of the invention.

I claim:

1. A longitudinally reciprocating concentrating table having a base, a deck, supports extending from the base and operatively engaged with the deck and resiliently yielding longitudinally and laterally, and means for giving a lateral movement to the discharge end of the deck when the deck is longitudinally reciprocated including a member pivotally mounted upon the base for oscillating movement on its pivot in a direction at an angle to the longitudinal movement of the

deck, said member being operatively connected at its free end to the discharge end of the deck whereby to cause the discharge end of the deck to be laterally shifted simultaneously with the longitudinal movement of the deck.

2. A concentrating table including a base frame, resilient supporting members attached to the base frame and extending upward therefrom and resiliently yielding in all directions, a deck operatively connected to the upper ends of the supporting members, and means at the discharge end of the deck for giving a lateral movement to the deck upon a longitudinal thrust at the head end of the table.

3. A concentrating table including a base frame, resilient supporting members attached to the base frame and extending upward therefrom and resiliently yielding in all directions, a deck operatively connected to the upper ends of the supporting members, and means at the discharge end of the deck for giving a lateral movement to the deck upon a longitudinal thrust at the head end of the table comprising a member pivotally mounted upon the base of the table for movement in a direction at an angle to the longitudinal movement of the deck, said member at its end having a rocking, operative engagement with the deck.

4. A concentrating table including a base frame, resilient supporting members attached to the base frame and extending upward therefrom and resiliently yielding in all directions, transverse beams operatively engaged at their ends with the supporting members, deck beams carrying the deck and operatively engaged with said transverse beams, and means for giving a lateral motion to the discharge end of the table comprising a member pivotally mounted upon the base frame for movement at an angle to the longitudinal movement of the deck and having its free end formed to have a rocking and sliding engagement with the end beam supporting the deck beam.

5. In a concentrating table having a base and a deck, resiliently yieldable supports attached to the base and operatively supporting the deck and yieldable resiliently in all directions, and means for giving a lateral movement to the deck upon a longitudinal thrust thereon comprising a member pivotally mounted upon the base for movement in a horizontal plane and in a direction at an angle to the direction of longitudinal movement, said member at its extremity being operatively connected to the deck, and means for adjusting said member to change its angle with respect to the longitudinal axis of the deck.

6. In a concentrating table having a base and a deck, resilient, yieldable supports attached to the base and operatively support-

ing the deck and yieldable equally in all directions, and means for giving a lateral, elliptical movement to the deck upon a longitudinal thrust thereon comprising a member pivotally mounted upon the base for angular movement, the free end of said member moving in a direction at an angle to the direction of longitudinal movement, said member at its extremity being engaged with but unattached to a portion of the deck whereby the deck may have a movement independent of said pivotally mounted member.

7. In a concentrating table having a base and a deck, resilient, yieldable supports attached to the base and operatively supporting the deck and yieldable equally in all directions, and means for giving a lateral, elliptical movement to the deck upon a longitudinal thrust thereon comprising a member pivotally mounted upon the base for movement in a horizontal plane and in a direction at an angle to the direction of longitudinal movement, said member at its extremity being slidingly connected to the deck, and longitudinally adjustable means extending at an angle to said member and operatively connected to the deck.

8. In a concentrating table having a base and a deck, resilient, yieldable supports attached to the base and operatively supporting the deck and yieldable equally in all directions, and means for giving a lateral, elliptical movement to the deck upon a longitudinal thrust thereon comprising a member pivotally mounted upon the base for movement in a horizontal plane and in a direction at an angle to the direction of longitudinal movement, said member at its extremity being slidingly connected to the deck, and longitudinally adjustable means extending at an angle to said member and operatively connected to the deck, comprising a link pivoted to said member, a fixed member attached to the deck through which the link passes, the link being adjustable with relation to said member to change the distance between the point of attachment of the link to the deck and said member.

9. In a concentrating table having a base and a deck, resilient, yieldable supports attached to the base and operatively supporting the deck and yieldable equally in all directions, and means for giving a lateral, elliptical movement to the deck upon a longitudinal thrust thereon comprising a member pivotally mounted upon the base for movement in a horizontal plane and in a direction at an angle to the direction of longitudinal movement, said member at its extremity being slidingly connected to the deck, and longitudinally adjustable means extending at an angle to said member and operatively connected to the deck, comprising a link pivoted to said member, a fixed member attached to the deck through which

the link passes, the link being adjustable with relation to said member to change the distance between the point of attachment of the link to the deck and said member, and a 5 nut engaging the link and bearing against the fixed member through which the link passes.

10. In a concentrating table including a base, resiliently yielding supports extending upward from the base and yielding in all directions, deck supporting beams mounted upon the supports, and means for giving a lateral movement to the discharge end of the deck, a base mounted upon the base frame 15 and having an upwardly extending socket, an arm having one end pivoted in said socket, the arm moving in a horizontal plane and in a direction at an angle to the longitudinal axis of the deck, said arm at its extremity being rockingly and slidingly engaged with the end deck supporting beam.

11. A concentrating table including a base, resiliently yielding supports extending upward from the base and yielding in 20 all directions, deck supporting beams mounted upon the upper ends of the supports, and means for giving a lateral, elliptical move- 25

ment to the discharge end of the deck comprising a base mounted upon the base frame and having an upwardly extending socket, 30 an arm having one end pivoted in said socket, the arm moving in a horizontal plane and in a direction at an angle to the longitudinal axis of the deck, said arm at its extremity being rockingly and slidingly engaged with the end deck supporting beam and said arm being provided with a flange having a series of openings disposed in line toward the center of motion of the arm, a bracket mounted on the end supporting 40 beam, and a link passing through said bracket, the link being screw-threaded, a nut mounted on the link and bearing against the exterior face of the bracket, and a pin operatively connecting the inner end of said 45 link in any one of said apertures in said flange.

In testimony whereof I hereunto affix my signature in the presence of two witnesses.

CHARLES C. HEBBARD.
